(57) **CLAIM**

The ornamental design for a ornamental design for a cover for preventing unauthorized access to a governor on an internal combustion engine, as shown and described.

DESCRIPTION

FIG. 1 is a perspective view of the invented governor access preventing cover, showing the new design; FIG. 2 is a layout of the invented cover for a governor prior to forming it by stamping and bending into its final shape as shown in FIG. 1; FIG. 3 is a top view of the governor cover of FIG. 1 after forming; FIG. 4 is a left side view of the device of FIG. 1; and FIG. 5 is a front view of the device of FIG. 1. FIG. 6 is a right side view of the device of FIG. 1; and, FIG. 7 is a bottom view of the device of FIG. 1.
